UNITED STATES PATENT OFFICE

ARCHIBALD G. SHAVER, OF CHICAGO, ILLINOIS

TRAFFIC CONTROL SYSTEM

Application filed June 14, 1927. Serial No. 198,823.

My invention relates to improvements in means for operating a track switch from a train.

It is the usual practice on railroads for a train, desiring to enter or leave the main line at a siding, to stop while a member of the crew walks ahead and operates a switch, except where the switch is connected with a tower or station and controlled by an operator. In the case of heavy freight trains, in particular, the stopping and starting of the train involves a great loss of energy, in addition to the time loss. In practicing my invention, these losses are eliminated by the provision of improved and efficient means for operating the switch without stopping the train.

One object of my invention therefore is to provide improved means for operating the track switch from the train, for example from the cab of the locomotive, without bringing the train to a stop.

Another object is to provide means whereby the track switch may be manually controlled from the train, from normal position to the reverse and automatically returned from reverse to normal position as soon as the train has cleared the track section in which the switch is located.

Another object is to provide practical means for operating the switch from the moving train through inductive means and without the necessity for physical contact between some part carried by the locomotive and a stationary part on the road-side.

Another object is to provide improved means on the locomotive or other part of the moving train for so controlling the inductor that the train cannot take the siding without slowing down.

A further object is to provide means, whereby, in connection with a spring connected track switch, a train on the main line may operate said switch and enter the siding, and after clearing the track circuit section,

the switch will return automatically to normal position, after which the train may move back onto the main line again, running through the points of the switch when in normal position without danger to said points.

A further object is to provide means whereby the engineman, when he acts to set the track switch for the siding, will be advised by a signal indication that the switch mechanism has started to function.

A further object is to provide means in a system, such as described, for informing the engineman when the track switch is in proper position for the train to pass over it.

An additional object is to provide in a system, such as described, means for preventing the switch from being operated when the track, including the switch and adjacent siding within the fouling points, is occupied by a train.

Other objects will appear from the drawing and accompanying descriptions relating to one embodiment of the invention.

In the drawing:

Figure 1 is a circuit diagram of the preferred form of my invention.

Fig. 2 is a modification of the circuit on the locomotive.

The track is divided into the usual track circuit sections S1, S2, S3, etc., which are insulated from each other in a well known manner, and each section is provided with a battery. Section S2 is shown as provided with a relay R2. The track circuit section S2 includes the siding as far as the fouling point F. This siding has the usual switch SW which is controlled by a combined switch stand and selector SS. A spring s is connected in the control rod of the switch in the usual way, so that the switch points will not be damaged when the switch is run through trailing.

The switch is actuated by a motor M which drives suitable power mechanism PM for opening and/or closing said switch. The

arrangement is such that either the switch stand or the power mechanism may be connected to the switch to permit manual or power operation. Before describing the circuits for actuating the motor, the circuit on the locomotive will be described.

The locomotive carries an inductor I, suitably located so as to pass near the stationary inductor I' without contacting with the same, the purpose being to induce a momentary current in the stationary inductor. The inductor circuit may assume various forms, as shown in Figs. 1 and 2. In Fig. 1, the inductor I may be energized by any suitable source of current, such, for example, as the battery B, connected thereto through suitable conductors 10, which circuit may be opened or closed by the centrifugal circuit closer C and/or by the switch contact H controlled by dashpot D and electromagnet E. Another convenient source of current is the headlight generator, or train control generator used on many trains. The switch H is normally in the position shown, that is, it is in lowermost position and closes a circuit through a signal lamp L, provided the train is running below a certain critical speed, whereby the centrifugal device C maintains the circuit closed at that point. When the train approaches the siding, it may be desirable to slow down, and when the speed has dropped below the required maximum, the signal light L will indicate that fact to the engineman. If the train is traveling too fast, the centrifugal device will hold the circuit open, thereby preventing the lamp from lighting. If the speed is low enough, the engineman closes the switch H by simply pushing upwardly on the small handle h, thereby energizing the electromagnet E and holding the circuit closed, whereby current flows through the inductor I as long as the speed continues below the maximum value. This switch forms the basis of my co-pending application, Serial No. 634,053, filed April 23rd, 1923, and issued August 28, 1928, as Patent 1,682,429. The inductor I, which is preferably a coil of wire, on a magnetic core, passes the stationary inductor I', which is of similar construction, thereby inducing current in the latter and closing the relay R1. The circuit from inductor I' to relay R1 is through conductors 11, 12.

Another relay R2 is connected across the rails of the section S2 and is therefore normally supplied with current from the battery B2, thus holding in closed position a series of contacts 14, 15, 16, 17, hereinafter referred to. When the train enters the section S2, the relay R2 is short circuited, and these four contacts fall open.

The motor circuit is controlled by a third relay R3, which actuates a pair of pivoted contacts 18, 19. This relay may be supplied with current from the battery B3 when the proper circuit is closed. This circuit is con-

trolled by relay R1 which, when energized, moves its armature 13 to establish a circuit from the battery B3 through conductors 20, 21, 22, contact 13, conductor 23, through the relay R3, conductor 24, contact 15, and conductor 25 back to the battery. The energized relay R3 lifts the contacts 18, 19, the former of which establishes the motor circuit through conductor 27, and the other of which is in a shunt circuit around contact 13 and therefore maintains the energization of the relay R3 after said contact 13 opens, as it does immediately after closing. The circuit to the motor is thus established from the battery B3, through conductors 20, 28, mechanically operated switching mechanism CC, motor M, conductor 27, contact 18, conductors 29, 24, contact 15 and conductor 25, back to the battery.

When the train has passed over the switch and has cleared the fouling point F, which is also the end of the track circuit in the siding, the relay R2 is again energized, thereby again completing the motor circuit and restoring the switch mechanism to normal or main track position. The mechanically operated circuit controller CC, shown diagrammatically in the drawing, is so arranged that as the motor is completing its rotation in one direction to open the track switch, the electric switch is moved to complete the motor circuit through conductor 26 for closing the track switch, and when the motor rotates in the opposite direction it leaves the electric switch in position closing the motor circuit through conductor 27 for again opening the track switch. Therefore, when the train has passed out of the section S2 and the relay R2 has closed the contact 15, the circuit of the motor is established through conductor 26, contact 18, conductors 29, 24, contact 15 and conductor 25, to the battery.

Means are provided whereby the engineman will be advised by signal indications that the switch operating means has started to function, and that the track switch is in proper position for the train to pass over it. These signals are indicated diagrammatically on the drawing 30, 31, 32. They are controlled by two circuit controllers SC and SO, actuated by the same mechanism which actuates the switch. In the drawing, the controller SC indicates the condition of the circuits when the switch is in normal position, and is actuated by the switch points. SO indicates the closed position of said circuits when the switch is properly locked in either of its two positions, said controller being actuated, for example, by the bolt which locks the switch against movement, or by other suitable means.

Signal 30 indicates that the main line is open, i. e. that the switch is in normal position. Signal 31 indicates "proceed", when the switch is open from the main line to the siding. Signal 32 indicates "proceed", when

the switch is properly set for a train to move from the siding to the main line. The switch must be properly positioned and locked before any signal can give the necessary indication to proceed.

The circuit for signal 30 is from common conductor C to the battery through the controlling mechanism of the signal, closed contact 14, conductor 33, circuit controller 34, closed when the track switch is normal, conductor 35, circuit controller contact 36, and continuing through other controlling elements of the block, if any, to the battery.

The circuit for signal 31 may, in like manner, be traced through contact 16, conductor 37, contact 38, normally open but closed when the switch is reversed, and contact 39.

The circuit for signal 32 is from the common conductor to the battery, through the controlling mechanism of the signal and through contact 40, closed when the switch is in position and locked, contact 41, closed only when the switch is open, conductor 42, contact 17, when closed, and on through other controlling features of the block, if any.

In Fig. 2, a somewhat modified locomotive inductor circuit is shown in which a generator 45, or other suitable source of current, energizes the inductor I3 when the switch H1 is closed and the circuit contacts 46, 47, are being bridged by a centrifugal device, similar to that previously described. An optional circuit is shown by dotted lines 49, whereby the centrifugal device may be omitted, if desired. When the engineman operates the hand-switch, the inductor I3 is energized, as in the previous case. Before the train enters the section S2, the engineman is compelled to slow down to a safe determined speed, and if this is done the current induced in the inductor I4 causes the operation of the various relays and motor circuits heretofore described, thereby opening the track switch. After the train passes the fouling point, the track switch automatically closes. It will thus be seen that the track switch is controlled by inductive means, that is current induced in a stationary circuit by a moving circuit on a train, as contrasted with mechanical means on the train moved by the train or electromagnet means, although certain phases of the invention may be used without reference to the manner in which the stationary circuit is closed by the moving train.

The track sections, shown in the drawing, are intended to be those used in connection with automatic block signals, but it will be understood that only one section of track need be insulated from the remainder when no block signals are used.

What I claim as new is:—

1. The combination with a main track, a branch track and a switch connecting the two, of speed governed train carried means co-operating with track means for operating

said switch on the approach of a train, and track means closing said switch after the train has passed the switch.

2. A railroad switch operating system comprising a mechanism for opening and closing the switch, a relay controlling the operation of the mechanism, and speed governed inductive train carried means for controlling the operation of the relay.

3. In a switch operating system, a power operated mechanism to open and close the switch, a source of power for said mechanism, a device for applying the power to the mechanism, and inductive train and track controlled means governing said device, effective only when the speed of the train is under a prescribed rate.

4. In a train controlled railway switch operating system, in combination, a stretch of track containing a switch, mechanism for operating said switch, a local relay controlling the operation of said mechanism, a track relay for said stretch of track, and an inductive device controlled by the speed of the train, and functioning to energize said local relay, to operate said switch, only when said track relay is energized.

5. In a train controlled railway switch operating system, in combination, a stretch of track containing a switch, mechanism for operating said switch, a local relay controlling said mechanism, a track relay for said stretch of track controlling both said local relay and said mechanism, and roadside means controlled from the train through an air gap, said roadside means when actuated energizing the local relay, but only when the track relay is energized.

6. In a train controlled railway switch operating system, in combination, a stretch of track containing a switch, a track relay for said stretch of track, mechanism for opening and closing said switch, a local relay for controlling said mechanism energizable only when said track relay is energized, and a device controlled from the train, said device functioning to energize the local relay to open the switch, and said track relay when deenergized functioning to deenergize said local relay for closing the switch after same has been opened.

7. In a train controlled switch operating system, in combination, a stretch of track containing a switch, mechanism for opening and closing the switch, a local relay controlling said mechanism in both the opening and closing movements, a track relay for the stretch of track, and a third relay operated from a source of energy on the train, said third relay being effective only when said track relay is energized for energizing the local relay to open the switch, and said track relay functioning to deenergize said local relay to close the switch after same has been opened.

8. In a train controlled switch operating system, in combination, a stretch of track containing a switch, mechanism for operating said switch, a circuit for operating said mechanism, a local relay operating said mechanism circuit, a circuit for said local relay, a track relay for said stretch operating said local relay and mechanism circuits, a third relay controlling said local relay circuit, and 10 a circuit controlled from the train through an air gap for operating said third relay, said third relay when operated closing the local relay circuit to energize the local relay to close the circuit for said mechanism, when 15 said track relay is energized.

9. A railroad switch operating system comprising mechanism for opening and closing the switch, a relay which when energized causes the mechanism to open the switch and 20 which when deenergized is adapted to cause the mechanism to close the switch, train carried means effective under prescribed speed conditions of the train to control the energization of said relay to stick the same as 25 the train approaches the switch and track means causing the deenergization of said relay when the train passes over the switch.

10. A railroad switch operating system comprising mechanism for opening and closing the switch, a relay which when energized causes the mechanism to open the switch, and which when deenergized is adapted to cause the mechanism to close the switch, and roadside means controlled by the train, but effective only under limiting speed conditions of 30 the train for energizing said relay as the train approaches the switch.

11. In a railway switch operating system, in combination, a stretch of track containing 35 a switch, mechanism for opening and closing said switch, a local relay, a source of energy for said mechanism and said local relay, a track relay normally energized, a circuit for said mechanism, a circuit for said local relay, a circuit contact in said mechanism and local relay circuits closed when the track relay is energized, a circuit contact in said mechanism circuit operated by said local relay closed when the local relay is energized, to operate the mechanism to open the track switch and closed when the local relay is deenergized to operate the mechanism to close the track switch, and roadside means controlled from a train for energizing said local 40 relay.

12. In a train controlled railway switch operating system, train carried means, including an electro-magnetic switch, for co-operating with roadside means to operate the railway switch, said train carried means becoming effective to operate the railway switch when the speed of the train is under a prescribed rate and the electro-magnetic switch 45 is closed, and being ineffective to operate said

railway switch when the speed of the train is above a prescribed rate.

13. In a train controlled railway switch operating system, train carried means, including a circuit closing switch, for co-operating with roadside means through an air gap to operate the railway switch, said train carried means becoming effective to operate the railway switch when the speed of the train is within prescribed limits and the circuit closing switch is closed. 75

14. In a train controlled railway switch operating system, in combination, a stretch of track containing a track switch, roadside means including a track relay for said stretch for operating said track switch, and train carried means controlled by an electro-magnetic switch for influencing said roadside means to operate said track switch providing said track relay is energized. 80

15. In a railway switch operating system, in combination, a stretch of track containing a switch; a mechanism for operating said switch; a local relay controlling circuit making contacts; a track relay for said stretch controlling circuit making contacts; a third relay controlling a circuit making contact; a source of energy; a circuit for said mechanism to operate said switch comprising said source of energy, a circuit making contact of said track relay closed when the track relay is energized and a circuit making contact of said local relay closed when said local relay is energized; a circuit for said local relay to energize the same comprising said source of energy, a circuit contact of said track relay closed when the track relay is energized and a circuit contact of said third relay closed when the third relay is energized; and train means for causing the energization of said third relay. 90

16. A railroad switch operating system comprising, a stretch of track containing a switch, a mechanism for operating said switch, a circuit including said mechanism, a local relay which when energized closes said circuit to operate the switch to one position and which when deenergized closes said circuit to operate the switch to another position, a track relay for said stretch controlling the local relay, and train carried means controlling the energization of the local relay as the train approaches the switch, and thereafter the sticking of said local relay in its own circuit through its own contact, said energization and said sticking being effected only when the track relay is energized. 100

17. In a train controlled railway switch operating system, in combination, a stretch of track containing a switch, a track relay for the stretch of track, a mechanism for opening and closing said switch, a local relay energizable only when said track relay is energized for operating said mechanism, and a device controlled from the train, said device 110

functioning to energize the local relay and stick the same to open the switch, and said track relay when deenergized functioning to deenergize said local relay to close the switch 3 after same has been opened.

18. In a train controlled railway switch operating system, in combination, a stretch of track containing a track switch, roadside means, including a track relay for said stretch, for operating said track switch, and train carried means including a circuit, a coil in said circuit and a switch controlled by said coil, for influencing said roadside means to operate said track switch providing said track relay is energized.

19. In a train controlled relay switch operating system the combination with a main track and a siding track and a track switch connecting the two, of train carried means, 20 including a circuit, a coil in said circuit and a switch controlled by said coil, co-operating with roadside means for operating the track switch in one direction on the approach of a train and track means for operating the track switch in the other direction after the train has passed said track switch.

20. In a train controlled railway switch operating system, in combination, a stretch of track containing a switch, mechanism for operating the switch, a control rod including a spring therein connecting said mechanism to the switch, a local relay controlling said mechanism, a track relay for said stretch of track controlling both said local relay and said mechanism and roadside means controlled from the train, said roadside means when actuated energizing the local relay when the track relay is energized.

21. In a system for producing track-side 40 operation from a train, in combination, operating means on the train, including a circuit, a coil in said circuit and means operative by the coil controlling said operating means, and trackside means comprising devices responsive to said operating means.

22. In a system of the character described, a stretch of main track containing a switch adapted when closed, for trains to operate along the main line, and, when opened, for 50 trains to operate between the main line and a siding, a first signal for governing trains over the switch along the main line, a second signal for governing trains over the switch from the main line to the siding, a third signal for governing trains from the siding to the main line, a mechanism for operating said switch and locking the same including a motor and a circuit for said motor, a track circuit for said stretch, a relay for said track circuit 55 operating in said motor circuit, contacts controlled by the operation of said track switch, a circuit for each of said signals controlled by said track circuit relay and by said contacts, the latter being closed when said track 60 switch is reversed for said second and third 65 switch is reversed for said second and third

signals to indicate proceed and when said track switch is closed for said first signal to indicate proceed, and train carried means co-operating with roadside means to operate said switch, said roadside means including 70 a controlling relay for said motor circuit, adapted, when energized, to be in position for said track switch to open and when de-energized for said track switch to close.

In testimony whereof, I have subscribed 75 my name.
